(57) **CLAIM**

The ornamental design for a connector for optical wiring, as shown and described.

DESCRIPTION

FIG. 1 is a front elevation view of the connector for optical wiring showing my new design;

FIG. 2 a rear elevation view thereof;

FIG. 3 is a top plan view thereof;

FIG. 4 is a bottom plan view thereof;

FIG. 5 is a right side elevation view thereof;

FIG. 6 is a cross-section of FIG. 1 along the 6—6 line;

FIG. 7 is a cross-section of FIG. 1 along the 7—7 line; and,

FIG. 8 is a perspective view thereof.
